US0D1037153S

(12) **United States Design Patent** (10) Patent No.: **US D1,037,153 S**
(45) Date of Patent: ** Jul. 30, 2024

(54) **POWER ADAPTER**

(71) Applicant: **Wenqiang Deng**, Suining (CN)

(72) Inventor: **Wenqiang Deng**, Suining (CN)

(73) Assignee: **Wenqiang Deng**, Suining (CN)

(**) Term: **15 Years**

(21) Appl. No.: **29/926,036**

(22) Filed: **Jan. 29, 2024**

(51) LOC (14) Cl. **13-02**

(52) U.S. Cl.

USPC **D13/110; D13/107; D13/108**

(57) **CLAIM**

The ornamental design for a power adapter, as shown and described.

DESCRIPTION

FIG. 1 is a front perspective view of a power adapter, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged partial view of area 9 in FIG. 3.

The dash-dash broken lines in the drawings illustrate the portions of the power adapter, which form no part of the claimed design.

The dash-dot-dash broken lines encircling the enlarged views are for annotative purposes only and form no part of the claim thereof.

1 Claim, 9 Drawing Sheets
